UNITED STATES PATENT OFFICE.

JOSEPH C. THEBERATH, OF LAKEWOOD, OHIO, ASSIGNOR TO RALPH A. ROHRICH, OF CLEVELAND, OHIO.

ENGINE-SUPPORT.

1,384,169.

Specification of Letters Patent. Patented July 12, 1921.

Application filed March 11, 1918. Serial No. 221,634.

To all whom it may concern:

Be it known that JOSEPH C. THEBERATH, citizen of the United States, residing at Lakewood, in the county of Cuyahoga and 5 State of Ohio, have invented a certain new and useful Improvement in Engine-Supports, of which the following is a full, clear, and exact description, reference being had to the accompanying drawings.

- 10 This invention relates to an engine supporting device, and more particularly to an auxiliary support for automobile engines (the term "automobile" being used in its broadest sense), the device being in the 15 nature of an attachment that may be readily applied to an automobile for the purpose of either relieving the usual engine supporting brackets of their load, or materially assisting them in sustaining it; or for the purpose of partially or wholly supporting the 20 engine in the event that one or both of its opposed brackets has or have been fractured.

A real need that has long existed gave rise to this invention. Much trouble is experienced, particularly in a present very popular 25 type of automobile, from the engine supporting brackets breaking, necessitating, if the work is properly done, the dismounting of the engines and the welding together of 30 the fragments of the brackets, incurring considerable expense and loss of time.

The objects of my invention are to provide a simple and inexpensive engine support that can be quickly installed without 35 the need of any tool other than a wrench, and that will securely hold the engine in place either supplemental to or independently of the supporting effect of any other means; that is adjustable to fit varying conditions, 40 and for placing it under desirable tension; and that is sufficiently flexible to readily yield to the usual torsions of the frame.

To these ends my invention may be defined as consisting of the combinations of 45 elements set out in the claims annexed hereto and illustrated in the drawing accompanying and forming a part hereof wherein Figure 1 is a perspective view of my engine support applied to the said members of an 50 automobile frame; Fig. 2 is a transverse section through the frame indicating the manner in which the engine is supported therefrom by the use of my invention; Fig. 3 is a plan view, with the engine shown in

dotted lines; and Fig. 4 is a section on the 55 line 4—4 of Fig. 3.

While I have illustrated my invention associated with a particular type of engine, it will be understood that the design of the support may be altered to adapt it to engines of other types without departing from the spirit of the invention, for I contemplate the use of the support in connection with all prevailing styles of engines wherein exists the weakness which I have hereinbefore explained.

In the drawing, I have conventionally shown an engine designated A, that is supported from the opposed side members B of an automobile frame by the usual crank case arms or brackets a. A spacer C is inserted between the web of each channel shaped frame member and the vertical branch of the corresponding bracket a, and a bolt a' passes through the frame member, 75 the spacer and the bracket, to hold the latter against side sway, while a bolt a² attaches the horizontal branch of the bracket to the top of the frame member. Due to the constant vibration of the engine when in operation, the lateral forces created by the tendency of the engine to swing within the frame, and the torsional strains imposed upon the brackets through the usual yielding of the frame, the brackets are weakened 80 and very often crack or break at the zone indicated by the arrow x in Fig. 4.

My auxiliary supporting device comprises anchorage elements 1 having lateral branches 2 turned downward at their outer 90 ends as indicated at 3 to embrace, between such down turned ends and the body portions of the elements the upper flanges of the side members B of the vehicle frame. An anchorage element is disposed on each side of each of the brackets a, and it depends slightly below the adjacent frame member to engage with the horizontal flanges of the engine casing that are indicated generally at a⁴. The surfaces of the anchorage members wherewith the flanges a⁴ contact are intended to be dressed off or finished so that the engine will accurately fit between the elements while said elements are in firm contact with the frame members. As a result 100 of these proportions, the engine is securely held against any possible side sway.

It may be explained that in the present en-

gine the brackets a are attached to the enlarged portion a^5 of the engine casing inclosing the fly wheel; and the bottom of this portion, constituting the lowest point of the casing is provided with a boss a^6 having an opening through which the oil may be drained from the casing, the opening being ordinarily closed by a plug a^7 . As previously stated the anchorage members 1 are located in juxtaposition to the brackets a , and consequently are in the zone of that portion of the engine casing inclosing a fly wheel. Suspension rods 5 extend beneath the engine and have their opposed ends turned outward and upward in parallel relation to each other to pass through vertical bores in the anchorage elements 1, the upper ends of the suspension rods being threaded for the application of nuts 7. A tie plate 8 is associated with each pair of anchorage elements, and it has its ends perforated for the passage of the rods 5, the plates being disposed between the nuts 7 and the ends of the elements thus serving to hold the elements against separation. Lock nuts 9 may be added to prevent the former nuts from loosening.

10 represents a saddle that is curved to conform to the underneath side of the portion a^5 of the engine casing, and it has a central aperture 11 for engagement over the boss a^6 ; and at each of its ends, the saddle is provided with opposed ears 12 that are turned downward to engage over the suspension rods 5 to hold them against separation. As indicated in the plan view of Fig. 3, the rods are drawn inward by the plate at their centers so as to strengthen the structure over what it would be if the rods were parallel, a sort of truss formation arising from this arrangement.

From the foregoing description it will be seen that my invention provides a very simple contrivance, wherein the parts may be easily assembled, and when assembled and installed, are very effectually held against displacement. Assuming that one of the brackets a is fractured at the point indicated by the arrow x in Fig. 4 it will be seen that by the application of my device, the engine may be drawn up into original position by the adjustment of the nuts 7 and 9 until the lower portion of the severed bracket is in firm engagement with the upper portion thereof, the upper portion constituting an abutment acting in opposition to the tension of the rods 5.

Having thus described my invention, what I claim is:—

60 1. An automobile engine support comprising a pair of suspension members arranged to pass side by side beneath the engine, means connecting the corresponding ends of the pair of members together and to the adjacent side members of the automobile frame,

and a saddle resting upon the suspension members intermediate their ends and supporting the engine and having parts engaged over said members thereby to hold them against separation. 70

2. An automobile engine support comprising two pairs of independent anchorage elements adapted to be arranged in opposed relation to each other, one pair for application to each side member of the automobile frame with one element on each side of the crank case arm, a pair of suspension members designed to pass side by side beneath the engine and have their corresponding ends connected to the anchorage elements of the adjacent pair, and a saddle resting upon the suspension members intermediate their ends and supporting the engine and having parts engaged over said members thereby to hold them against separation. 75

3. An automobile engine support comprising two pairs of anchorage elements adapted to be arranged in opposed relation to each other, one pair for application to each side member of the automobile frame, each element having a bore, a pair of suspension rods designed to pass beneath the engine and have their corresponding ends passed upward through the bores of anchorage elements, a member having apertures for the passage of the rods and adapted for application to the ends of the rods projecting above the elements of each pair, and means for application to the ends of the rods preventing their withdrawal from the elements. 80

4. An automobile engine support comprising a pair of suspension members arranged to pass beneath the engine, means connecting the corresponding ends of the pair of members together in spaced relation to each other and to the adjacent side member of the automobile frame, and a saddle sustained by the suspension members and having parts coöperating therewith to maintain the central portions of said members closer together than their corresponding ends. 100

5. An automobile engine support comprising a pair of anchorage elements adapted for application to each side member of the automobile frame, each element having a bore, a pair of suspension rods arranged to pass beneath the engine and having their ends extended upward through the bores of the anchorage elements, a perforated plate for application to the ends of the rods protruding above each pair of elements, the ends of the rods being threaded, nuts for application to the ends of the rods, and a saddle sustained by the central portions of the suspension rods and having opposed lugs overhanging said rods to maintain them against separation, the saddle having an aperture for coöperation with a protuberance of the engine. 115

6. An automobile engine support comprising 120

ing a pair of anchorage elements adapted for application to each side member of the automobile frame, each element having a bore, a pair of suspension rods arranged to 5 pass beneath the engine and having their ends extended upward through the bores of the anchorage elements, a plate perforated for application to the ends of the rods protruding above each pair of elements, the 10 ends of the rods being threaded, nuts for application to the ends of said rods, and a saddle sustained by the central portions of the suspension rods and having opposed lugs overhanging said rods to maintain them 15 against separation, the saddle having an aperture for coöperation with a protuberance of the engine, and the anchorage elements being designed to fit between the sides of the engine and the opposed side members of 20 the automobile frame thereby to prevent

side sway of the engine with respect to the frame.

7. An automobile engine support comprising anchorage elements for application to the opposed side members of the automobile 25 frame, each element consisting of a body portion having a lateral branch, hooked at its outer end, and adapted to be engaged over the upper side of the frame member, each element having a bore, and an abutment surface disposed to be engaged by a part of the engine, a suspension rod designed to pass beneath the engine and have its ends passed upward through the bores of the elements, the ends of the rod being threaded, and nuts 30 for application to the ends of the rods above the elements.

In testimony whereof, I hereunto affix my signature.

JOSEPH C. THEBERATH.
